REMOTE CONTROLLING APPARATUS

Clarence S. Snavely, Pittsburgh, Pa., assignor to
 The Union Switch & Signal Company, Swiss-
 vale, Pa., a corporation of Pennsylvania

Application July 17, 1929, Serial No. 378,894

74 Claims. (Cl. 246—3)

My invention relates to remote controlling apparatus, and particularly to apparatus adapted to be used in a centralized traffic controlling system for railroads for controlling a plurality of train governing devices, such as railway switches or signals, from a central point, such for example, as a train dispatcher's office, and for also indicating at said office the condition of such devices and traffic conditions adjacent such devices, such as the presence of trains adjacent the devices.

It is customary in systems of the type described to deliver control codes to a line circuit extending between the dispatcher's office and the remote point at which the governing devices are located for effecting the control of these devices, and for delivering indication codes to this line circuit from the remote point for informing the operator at the dispatcher's office concerning the condition of the devices and also concerning traffic conditions adjacent such devices. The codes usually employed for these purposes are made up of code elements having different lengths, or different numbers of impulses, and the receiving apparatus is selectively responsive to the lengths of these code elements or to the number of impulses in each code element. I propose to utilize code elements having different characters, not requiring time measurement or counting devices to distinguish between them, and I also propose to provide separate devices selectively responsive to each such code element. With this arrangement, the receiving apparatus is arranged to respond selectively to the sequence of operation of these devices and the system is therefore independent of the lengths of time required for the separate code elements.

The apparatus of my invention is an improvement upon that disclosed in my copending application, Serial No. 362,948, filed May 14, 1929, for Remote controlling apparatus, and also upon that disclosed in an application by Lloyd V. Lewis, Serial No. 291,465, filed July 9, 1928, for Remote controlling apparatus.

I will describe one form of remote controlling apparatus embodying my invention, and will then point out the novel features thereof in claims.

In the accompanying drawings, Figs. 1 and 2, when placed end to end with Fig. 1 on the left form a diagrammatic view illustrating one form of remote controlling apparatus embodying my invention, Fig. 1 showing the equipment located at the control office and Fig. 2 showing the equipment located at a field station. Fig. 3 is a sectional view showing one form of decoding relay

suitable for use in the apparatus illustrated in Figs. 1 and 2. Figs. 4, 5 and 6 are sectional views along the lines IV—IV, V—V and VI—VI, respectively, of Fig. 3. Fig. 7 is a detail view of a portion of the decoding relay shown in Fig. 3 as it would appear if viewed along the arrow VII in Fig. 6.

Similar reference characters refer to similar parts in each of the several views.

Referring first to Fig. 1, I have shown the equipment at the office for transmitting codes made up of code elements of different characters. In the particular embodiment here shown, each code element is an impulse of periodic current of a distinctive frequency and these currents are supplied by three alternators X, Y and Z which are driven by a motor m comprising an armature 5 and a field 6. The armature 5 is constantly connected across the terminals B and C of a source of energy not shown in the drawings. The field 6 is connected with terminals B and C through a resistance 7 which is at times shunted by a contact 8 of a centrifugal governor h operated by motor m. With this arrangement, it will be apparent that the motor m operates at a constant speed, and since the alternators X, Y and Z are operatively connected with this motor, it follows that the frequencies of the currents delivered by these alternators are substantially constant.

Means are provided for selectively connecting the alternators X, Y and Z with a pair of line wires 3 and 1 which extend from the office to each of the remote stations at which there are located devices which it is desired to control from the office. The connections of the alternators to these line wires are controlled by three delivery magnets each designated by the reference character AD with an exponent corresponding to the associated alternator. For example, when delivery magnet AD^X is energized, the front contact 9 of this magnet is closed and alternator X is then connected across line wires 1 and 3. In similar manner, the energization of magnet AD^Y connects alternator Y across line wires 1 and 3, and the energization of magnet AD^Z connects alternator Z across line wires 1 and 3.

The delivery magnets AD^X , AD^Y and AD^Z are controlled in part by a distributor comprising a stepping contactor P^A operated by a magnet F^A . This stepping contactor is similar in all respects to the stepping contactor which is described and claimed in my copending application for Letters Patent, Serial No. 362,948, hereinbefore referred to. This stepping contactor com-

prises a spider 33 operated by a pawl 34 driven by magnet F. The spider co-operates with a plurality of fixed contact segments, designated by the reference characters 35 to 40, and arranged in such manner that an arm of the spider engages one of these segments at all times. As shown in the drawings, the spider engages segment 35. If, now, the magnet F^A is energized, pawl 34 is moved along one step on the spider 33, and when the magnet F^A is next de-energized, the spider 33 is advanced one step so that an arm of the spider then engages contact 36. In similar manner, successive energizations and de-energizations of the stepping magnet F^A advance the spider 33 from each segment of the stepping contactor to the next segment in order. Associated with the stepping contactor P^A is a master relay J^A, a starting relay x and two timing relays i^A and j^A, the functions of which will be described hereinafter.

The control office is provided with a plurality of panels, one for each remote station which is to be controlled from the office, and each panel is provided with manually oscillatable switching devices for separately controlling governing devices at the associated station. Referring particularly to panel B on Fig. 1, this panel is provided with two switching devices BE¹ and BE², each comprising a lever 12 in the form of a cam which operates a cam follower 13. The lever 12 also controls a movable contact 14 which may be moved into engagement with a selected one of a plurality of fixed contacts. The switching devices BE¹ and BE² are employed as the control levers for the track switch and for the signals at station B of Fig. 2, and as herein illustrated, are mounted upon a panel board or track model having a miniature representation of the track layout on the face thereof. The portion of the track diagram allocated to panel B includes a miniature movable switch point in a location corresponding to that of the track switch at station B, and provided with a handle 27 by which it may be moved in a plane parallel to the panel to a normal or reverse position to indicate the route to be taken by a train in passing over the switch. Handle 27 is operatively connected to the lever 12 of switching device BE¹ as indicated by a dotted line connection on the drawings, so that when the miniature switch point is moved to normal or reverse to visually indicate the position to be assumed by the track switch lever 12 of device BE¹ is moved to a corresponding position. The signal control lever has a handle 28 on the face of the panel, which is provided with a pointer for indicating the direction of train movement established over the track switch, and also with a connection, as indicated by a dotted line on the drawings, for operating the lever 12 of switching device BE². The portion of the track model which is allocated to panel B is also provided with a plurality of indication lamps 29, 30, 31 and 32, which are controlled as will be described hereinafter for informing the operator of the condition of the apparatus under the control of the handles 27 and 28. For purposes of simplicity, panel B is the only one which is illustrated complete in the drawings portions only of two other panels designated C and D being illustrated in Fig. 1.

Referring now to panel B, the switching devices BE¹ and BE² control a starting contact comprising a movable member 18 which is pivoted at point 18^a and which is arranged to move to the left when the lever of either switching device is operated. When the member 18 is urged to the

left, contact arm 20 is moved out of engagement with contact 22, which it normally engages, and is swung into engagement with contact 21. This movement of arm 20 permits a latch 23 to drop under the influence of gravity to a position in which the return of the arm 20 is prevented.

Each panel is also provided with a code determining or code sending relay, designated by the reference character W with a prefix corresponding to the location, and having a winding 25 which controls a finger 24 and a plurality of contacts. When winding 25 of relay BW is energized, the finger 24 is swung to the left, and the tip of this finger then engages the arm 20, and at the same time lifts the latch 23. Under these conditions, therefore, the arm 20 is unlatched, but is held in its left-hand position, so that contact 20-21 is closed, until winding 25 is de-energized.

The switching device BE¹ as already pointed out, is employed to operate the track switch at the corresponding remote station and when the handle 27 occupies the position shown in the drawings, contact 14-16 operated by lever 12 is closed. If the handle 27 is operated to its reverse position, however, contact 14-15 becomes closed. The handle 28 which operates switching device BE² is utilized to govern the railway signals at the same station and when this handle occupies the position illustrated in the drawings, contact 14-16 of switching device BE² is closed. If handle 28 is swung to the left, contact 14-17 is closed and if handle 28 is swung to the right, contact 14-15 is closed.

The line wires 1 and 3 extend to all of the remote stations which are controlled from the office in Fig. 1, line wire 3 serving as a common return and line wire 1 including in series a transformer at each way station. Referring particularly to Fig. 2, it will be seen that the primary of transformer t^B is included in series with line wire 1 at station B and similar transformers are located at each of the other stations.

Governing devices of any suitable type may be controlled by apparatus embodying my invention, but for the purposes of explanation I have illustrated at station B, a section of power operated railway track a-b provided with a railway switch 50 leading into a siding 51. The section a-b is provided with a track circuit including a battery 52 connected across the rails adjacent one end of the section and a track relay v connected across the rails adjacent the other end of the section. The switch 50 is controlled by a motor g comprising an armature 53 and a field 54, which motor is controlled in part by two switch relays p¹ and p². Switch 50, in turn, controls a pole changer 55 which governs the polarity of current supplied from terminals B and C to an indication relay k, as will be apparent from the drawings. Relay k is energized in the normal direction, so that its polar contacts are swung to the left, when switch 50 occupies its normal position. When the switch 50 occupies its reverse position, however, relay k is energized in the reverse direction, so that its polar contacts are swung to the right. When switch 50 occupies any intermediate position, indication relay k is de-energized so that its front contacts are open. Switch 50 also controls two contacts 56 and 57. Contact 56 is closed at all times except when the switch occupies its full reverse position, and contact 57 is closed at all times except when the switch occupies its full normal position.

Eastbound traffic through the section a-b is 75

controlled by two signals w^1 and w^2 which, as here shown, are mounted upon the same mast. In similar manner, westbound traffic is governed by two signals w^3 and w^4 . The signals w^1 , w^2 , w^3 and w^4 are controlled in part by two signal relays q^1 and q^2 .

The switch relays p^1 and p^2 and the signal relays q^1 and q^2 at station B are controlled by receiving apparatus which will be described in 10 detail hereinafter.

As shown in the drawings, the switching devices BE^1 and BE^2 on panel B at the control office occupy their normal positions and switch 50 at station B occupies its normal position. 15 Switch relays p^1 and p^2 are both deenergized, and the signal relays q^1 and q^2 are also deenergized so that all signals at station B occupy their stop positions. In explaining the operation of the apparatus as a whole, I will first assume that the 20 operator wishes to reverse switch 50 at station B. In order to accomplish this result he moves the handle 21 of switching device BE^1 to the reverse position indicated by the dotted lines in the drawings. As a result, the cam follower 13 25 operated by switching device BE^1 is moved to the left, thereby swinging member 18 to the left and closing contact 20-21. At the same time, contact 19 is opened. Latch 23 now engages the arm 20 and holds this arm in engagement 30 with contact 21. When the handle 21 has reached its full reverse position, member 18 returns to the position in which it is shown in the drawings, thereby closing contact 19, but contact 20-21 remains closed. A circuit is now 35 completed from terminal B, over back contact 42 of relay x, contact 43-43^a of master relay J^A , resistance 44, contact 20-21 of panel B, contact 19 operated by member 18 of panel B, and winding 25 of relay B^W to terminal C. Relay B^W 40 therefore becomes energized, and moves finger 24 to the left. This operation releases latch 23, but closes contact 20-24 and holds the arm 20 in engagement with contact 21. It should also be noted that this operation of finger 24 closes the 45 group of code setting contacts located to the right of the finger in the drawings. When contact 20-24 closes, current flows from terminal B, over back contact 42 of relay x, winding 58 of relay J^A , contact 24-20 of panel B, contact 50 20-21 of panel B, contact 19 and winding 25 of relay B^W to terminal C. The potential drop across resistance 44 insures a sufficient electro- 55 motive force to energize winding 58 over the circuit just traced. As a result, relay J^A reverses, to close contact 43-43^b. Contact 43-43^a of relay J^A is now open, so that the circuit first traced for winding 25 is interrupted, but this winding is now held energized over the circuit 60 last traced until relay x becomes energized, as will be explained hereinafter.

Relay J^A , and likewise the relay J^B of Fig. 2 and also those relays herein disclosed bearing the general reference r or L are of the stick polar 65 type, and it is to be understood that each of these relays is adapted to be operated by a momentary impulse of current and to maintain its contact closed in the last-operated position when de-energized.

The closing of contact 43-43^b of relay J^A 70 energizes stepping magnet F^A of stepping contactor P^A over a circuit which passes from terminal B, over back contact 42 of relay x, contact 43-43^b of relay J^A , winding of magnet F^A , and 75 back contact 45 of relay J^A to terminal C. This

energization of magnet F^A does not move the spider 33 of the stepping contactor, but front contact 48 of the magnet is closed so that terminal B is connected with the spider 33 which is now in engagement with the fixed segment 35. 8 Each segment of the stepping contactor is connected with a selected one of the delivery magnets AD^X , AD^Y or AD^Z , depending upon the connections which are controlled by the contacts actuated by the relay B^W of panel B. For convenience, the segments of the contactor are brought out to bus bars and the delivery magnets are also connected with bus bars, cross connections between these two sets of bus bars being controlled, in part directly by the contacts 10 of the code sending relays, and in part by the position of the switching devices at each panel. The first four code elements of each control code are utilized for selecting a particular station and these code elements are the same for all 15 codes originating at the same panel, the remaining two elements of the code being utilized for operating a particular function at the selected station, and being dependent upon the position of the switching device of the particular panel. 20

For purposes of explanation, I will assume that the first element of the code necessary for selecting station B consists of an impulse of current of the frequency supplied by alternator Y, and that the bus for connections are made accordingly. When stepping magnet F^A becomes energized, a circuit is completed from terminal B, over front contact 48 of magnet F^A , contact 33-35 of stepping contactor P^A , contact 49 of code setting relay B^W , and winding of delivery 25 magnet AD^Y to terminal C. The delivery magnet AD^Y therefore becomes energized, and the closing of contact 10 of this magnet connects alternator Y across line wires 1 and 3, and delivers an impulse of current from alternator Y to the line wires to form the first code element. When the stepping magnet F^A became energized, front contact 46 closed, and current was supplied from terminal B, over front contact 46 of magnet F^A , and winding of relay i^A to terminal 30 C. Relay i^A therefore becomes energized. Relay i^A is then connected directly with the terminals B and C, over front contact 47 of relay i^A . When relay i^A becomes energized, the opening of back contact 45 of this relay interrupts the circuit previously traced for the stepping magnet 35 F^A . When magnet F^A releases, it opens front contacts 46 and 48, and advances the spider 33 one step into engagement with segment 36. The opening of front contact 48 of magnet F^A 40 interrupts the circuit for the delivery magnet AD^Y and terminates the first element of the code. Furthermore, the opening of front contact 46 of this magnet de-energizes relay i^A and this relay in turn releases relay j^A . When back contact 45 of relay j^A closes, a circuit is again completed for the stepping magnet F^A and when this magnet becomes energized, energy is supplied to the delivery magnet which is connected with segment 45 36, (in this case delivery magnet AD^X), so that the second element of the code is made up of an impulse of current of the frequency supplied by alternator X. The energization of magnet F^A also sets the relays i^A and j^A into operation as described hereinbefore, to de-energize the magnet F^A , terminating the second impulse of the code and advancing spider 33 of the stepping contactor P^A into engagement with segment 37. The operation just described is repeated for the 50 55 60 65 70 75

third and fourth elements of the code, the circuits being apparent from the drawings without tracing them in detail. It should be noted, however, that as here shown the third element of 5 the code is supplied by alternator Z, and the fourth element of the code is supplied by alternator Y. After the delivery of the fourth element of the code, the spider 33 is in engagement with segment 39 and when the magnet F^A next 10 becomes energized, the fifth element of the code is supplied to line wires 1 and 3 in accordance with the position of the switching device BE¹ which as previously described, controls the track switch at station B. Since lever 21 has been 15 reversed, contact 14-15 of this switching device is closed, so that the fifth impulse of the code is supplied by alternator Y. In similar manner, the sixth impulse of the code is controlled by 20 the position of the switching device BE², which now occupies its normal position, so that its contact 14-16 is closed and the sixth element of the code is therefore also supplied by alternator Y.

The de-energization of magnet F^A following 25 the sixth element of the code advances the spider 33 into engagement with segment 41 and when magnet F^A next becomes energized, current flows from terminal B, over front contact 48 of magnet F^A, contact 33-41 of stepping contactor P^A, and winding of relay x to terminal C. Relay x therefore becomes energized and interrupts, at back contact 42 thereon, the holding circuit for relay BW of panel B. This relay therefore becomes de-energized and releases the finger 24. 30 Since this finger now holds latch 23 out of engagement with the arm 20, the release of relay BW allows arm 20 to return to its original position to close contact 20-22. Furthermore, the closing of front contact 42 of relay x energizes 35 the winding 59 of relay J^A, thereby energizing this relay in its normal position and closing contact 43-43^a. The opening of the contact 43-43^b of the master relay J^A interrupts the circuit for stepping magnet F^A and advances the 40 spider 33 into engagement with segment 35. Relay x is therefore de-energized, and relays F^A and J^A are de-energized so that all portions of the apparatus are restored to the positions in which 45 they are shown in the drawings, and the equipment is again ready to initiate the transmission of a control code to the line circuit.

During the operations just described, it will be apparent that line wires 1 and 3 have been supplied with a code made up of six code elements, each element being an impulse of current of a selected frequency, the sequence of these frequencies being determined in part by the panel from which the code originated and in part by the 50 positions of the switching device at that panel.

Referring now to Fig. 2, it will be clear that any code originating at the control office, and supplied to line wires 1 and 3, traverses the primary of transformers t^B at station B. The secondary of this transformer therefore has induced in it, impulses of current, the frequencies of which correspond to the frequencies of the code elements supplied to line wires 1 and 3.

Each station is provided with a plurality of devices which are selectively responsive to the different characters of code elements supplied to the line wires. For example, these devices may be ordinary relays included in circuits which are tuned respectively to resonance at the frequency 75 of the several code elements. As shown in Fig.

2, the secondary of transformer t^B supplies energy to three relays BG^X, BG^Y and BG^Z. The circuit including relay BG^X, is tuned to resonance, as by a reactor 60 and a condenser 61, so as to provide a communication channel which is selectively responsive to current of the frequency supplied by alternator X. Relay BG^X will therefore close its front contact only in response to a code element supplied from alternator X at the dispatcher's office. In similar manner, 10 relays BG^Y and BG^Z are tuned to resonance at the frequencies of the currents supplied by alternators Y and Z, respectively, so that relay BG^Y closes its front contact only in response to a code element supplied by alternator Y, and relay BG^Z 15 closes its front contact only in response to a code element supplied from alternator Z. The reference character BH designates a relay which is also supplied with energy from the secondary 20 of transformer t^B and is arranged to be energized when any code element is being supplied to the line wires 1 and 3. Relay BH is somewhat slow-acting, so that this relay becomes energized at the beginning of any control code and remains 25 energized until the conclusion of the code.

In response to the control code previously described, therefore, relay BH at station B is energized at all times during the reception of this code, and selected ones of relays BG^X, BG^Y and BG^Z are energized successively in a definite sequence depending upon the sequence of the several current impulses of different frequencies forming the control code.

It is desirable to control the apparatus at the remote station in accordance with the sequence of operation of the relays G at that station. For this purpose, I provide at each station, a plurality of decoding relays which are controlled by the associated relays G to respond selectively to specific control codes. These decoding relays are designated by the reference characters N with prefixes corresponding to the location, and with suitable distinguishing exponents. Decoding relays operating in the manner described may be constructed in a number of ways, and I have illustrated only one form of decoding relay and wish it to be particularly understood that I do not limit myself to this particular embodiment.

Referring now to Figs. 3 to 7, inclusive, I have illustrated in detail one form of decoding relay N suitable for use in apparatus embodying my invention. This relay comprises a housing 150 provided with a cover 151 and containing a plurality of stepping magnets and a holding magnet. The holding magnet is designated by the reference character 62^H, and one of the stepping magnets is provided for each of the associated relays G and each is designated by the reference character 62 with an exponent corresponding to the frequency of the code element during which the stepping magnet is energized. As here shown, the holding magnet and the stepping magnets are arranged side by side on a magnetizable core 63 which is provided with outstanding legs 65 71, as best seen in Fig. 6, certain of such legs thus forming parts of the magnetic circuits for adjacent stepping magnets. The decoding relay N also comprises a rotatable shaft 66 supported in suitable journals, and biased, by means of a spring 67, to the position in which it is shown in the drawings, and in which position a contact arm 68 on the shaft engages a fixed stop 69. Rigidly attached to the shaft 66 are a plurality 70 of driving disks each designated by the reference 75

character 64 with a suitable distinguishing exponent. Each of these disks is provided with a plurality of openings 80 (see Fig. 6) which may be provided with magnetizable slugs 76. Pivotally supported on trunnions 14 between each two magnetizable legs 71 is a stepping yoke comprising a T-shaped element 73 (see Fig. 7) of non-magnetic material to the opposite sides of which are attached two spaced magnetizable fingers 75 which are disposed on opposite sides of the associated driving disk 64. As best shown in Fig. 6, each element 73 with its associated fingers 75 is biased, by means of a spring 77, against an adjustable stop 78. When the parts occupy these positions, the fingers 75 are adjacent to, but out of alignment with, enlarged pole pieces 72 attached to the extremities of the adjacent legs 71. As shown in Fig. 6, a slug 76 occupies the opening 80 which is between the fingers 75. If, now, the stepping magnet 62^X becomes energized, the element 73 with the associated fingers 75 is rotated in a clockwise direction by the tendency of the fingers 75 to move into alignment with the pole pieces 72. During this movement, the flux from the magnet 62^X also passes between fingers 75 through the slug 76, so that when the fingers move, as described above, the driving disk 64^X is also moved. Each of the stepping magnets controls a driving disk in the manner just described. The holding magnet 62^H, illustrated in Figs. 4 and 5, is provided with two upstanding magnetizable legs 79 terminating on opposite sides of the holding disk 64^H which is provided with a plurality of slugs 76 similar to those described in connection with the driving disks. The holding disk is provided with slugs corresponding to every stepping position of the shaft 66, whereas, slugs are inserted in the driving disks only in those openings 80 corresponding to the positions in which it is desired that an energization of the associated magnet should advance the shaft 66. As illustrated in Fig. 6, for example, the disk 64^X has only two slugs 76 so positioned that this particular disk can advance shaft 66 only if winding 62^X becomes energized during the first or the fourth element of a code. To facilitate adjustment of the slugs 76, the openings 80 may be partially covered by a retaining plate 65 (see Figs. 5 and 6), and provided with a slot 91 which may be brought opposite any opening to permit the withdrawal or insertion of a slug. The parts are so proportioned that if the driving magnets are energized in a predetermined sequence corresponding to a definite control code, the last code element will rotate the shaft 66 to a position in which the arm 68 engages a fixed contact 70.

As indicated in Fig. 3, each stepping magnet is connected with terminals B and C over front contact 152 of the corresponding holding relay H and a front contact of the corresponding stepping relay. The holding magnet, however, is energized over a front contact of the holding relay and back contacts of all of the stepping relays in series.

The decoding relay illustrated in the drawings is designed for operation upon codes having six elements. For example, if it were desired to adjust the relay shown in Fig. 3 to respond to the control code supplied as described hereinbefore to the line wires 1 and 3 for reversing the switch at station B, slugs 76 would be placed in openings 80 in the driving disk 64^X corresponding to the first, fourth, fifth and sixth steps in the rotation of shaft 66. Furthermore, a slug would be

placed in the opening 80 of driving disk 64^Z corresponding to the third driving position and a slug would be placed in the opening 80 of disk 64^X corresponding to the second driving position. With the parts constructed in this manner, the first code element received energizes relays H and G^Y, Fig. 3. Since driving disk 64^Y has a slug in the first position, the operation of the stepping magnet 62^Y in response to operation of relay G^Y advances the shaft 66 one step. At the conclusion of the first code element, relay G^Y becomes de-energized but relay H remains closed due to its slow releasing characteristics, so that the holding magnet 62^H is energized, thereby holding the shaft 66 in the position to which it has been moved, and bringing the second opening 80 of each driving disk into position to be operated upon by the corresponding fingers 75. During the second code element, relay G^X becomes energized and since the driving disk 64^X has a slug in the second position, the energization of stepping magnet 62^X advances the shaft 66 another step. The operation of the decoding relay N during subsequent code elements, will be readily understood from the foregoing, it being necessary here to state only that a decoding relay N cannot be operated to close its contact 68-70 unless its stepping magnets are energized in a definite predetermined sequence.

It should also be pointed out that if a decoding relay has been partially operated, so that its shaft 66 is rotated away from its initial position, and a code element is received which energizes a stepping magnet for which there is no slug in the driving disk, the opening of the circuit for the holding magnet during this code element allows the shaft 66 to return to its initial position, thereby effectively preventing the operation of the contacts 68-70 in response to any code except the particular one for which the decoding relay is designed to operate.

Returning now to a consideration of Fig. 2, the decoding relays N at station B are constructed to respond selectively to the control codes originating at panel B of the dispatcher's office. For example, in response to the control code delivered when handle 27 on panel B is moved to its reverse position, the decoding relay BN³ at station B closes its contact 68-70 for a brief interval of time. During this interval, current flows at station B, from terminal B through winding 81 of relay BL³, contact 68-70 of decoding relay BN³ and winding 82 of relay BL² to terminal C. Relay BL² was already energized in its reverse position so that this relay suffers no change as a result of the operation of relay BN³. Relay BL³ now becomes energized in its reverse direction, however, and when this happens, the closing of contact 83-83^b of relay BL³ completes a circuit from terminal B, over contact 83-83^b, contact 56 operated by switch 50 and winding of switch relay p² to terminal C. Relay p² therefore becomes energized and motor g is then actuated by current which flows from terminal B, over front contact 84 of track relay v, front contact 85 of switch relay p², armature 53 of motor g, front contact 86 of relay p² and field 54 of motor g, to terminal C. When this circuit is closed, motor g operates to drive switch 50 toward its reverse position. When the switch has attained its full reverse position, contact 56 opens, thereby interrupting the circuit for relay p² and allowing this relay to release and de-energize the motor g.

If the operator wishes to restore the switch at 75

station B to its normal position, he may do so by restoring the handle 27 on panel B to its normal position. When this happens, the operation of the cam 12 actuates the transmitting apparatus 5 at the office in the same manner as previously explained and a control code is then delivered to line wires 1 and 3 which is identical to that previously described except that the fifth element of this code is now made up of an impulse of current supplied by alternator X, since contact 14-16 operated by handle 27 is now closed and as a result the delivery magnet AD^X is connected with the segment 39 of the stepping contactor PA to produce the fifth element of the code. When 10 this code is received at station B, the decoding relay BN⁴ is the only relay which closes its contact 68-70. When this happens, current flows from terminal B, through winding 87 of relay BL³, contact 68-70 of decoding relay BN⁴, and winding 20 82 of relay BL² to terminal C. Relay BL² remains in its reverse position, but relay BL³ is now restored to its normal position, whereupon current flows from terminal B, through normal contact 83-83^a of relay BL³, contact 57 operated by 25 switch 50, and winding of switch relay p¹ to terminal C. When relay p¹ becomes energized an operating circuit is closed for motor g from terminal B, over front contact 88 of track relay v, front contact 89 of relay p¹, armature 53 of motor 30 g, front contact 90 of relay p¹, and field 54 of motor g to terminal C. Motor g is then actuated to drive switch 50 toward its normal position and when the switch attains its full normal position, contact 57 opens, thereby de-energizing relay p¹ 35 and stopping the motor g.

In similar manner, the signals at station B are selectively controlled by the remaining decoding relays at this station. For example, if the operator wishes to clear the eastbound signal at station B, he operates handle 28 to its right-hand position, thereby delivering to the line wires 1 and 3 a control code which actuates the relays BG^X, BG^Y and BG^Z at station B in a sequence which energizes decoding relay BN⁶ at station 40 B. When this relay closes its contact, current flows from terminal B, through winding 81 of relay BL³, contact 68-70 of relay BN⁶, winding 92 of relay BL¹, and winding 93 of relay BL² to terminal C. Relays BL³ and BL¹ therefore remain in the normal position, and relay BL² also becomes energized in the normal direction. When this happens, current flows from terminal B, through contact 94-94^a of relay BL², contact 50 55 95-95^a of relay BL¹, and winding of relay q¹ to terminal C. Relay q¹ therefore becomes energized and since switch 50 now occupies its normal position so that indication relay k is energized in the normal direction, this operation of relay q¹ clears the signal w². The operating circuit for this signal may be traced from terminal B, over front contact 96 of relay v, front contact 60 97 of relay q¹, front contact 98 of relay k, normal contact 99 of relay k, and operating mechanism of signal w² to terminal C.

65 I will next assume that switch 50 at station B occupies its reverse position and that the operator moves handle 28 to its right-hand position to clear the eastbound signal. The control code, then delivered from panel B, actuates decoding 70 relay BN⁵. When this happens, current flows from terminal B, through winding 81 of relay BL³, contact 68-70 of relay BN⁵, winding 92 of relay BL¹, winding 93 of relay BL² to terminal C. As a result, relays BL¹ and BL² are both energized in the normal direction and relay BL³ is

energized in the reverse direction. Current then flows from terminal B over normal contacts of relays BL¹ and BL² to energize relay q¹ as described hereinbefore. Since the switch now occupies its reverse position, however, the indication relay k is energized in its reverse direction and the signal operating circuit now completed is from terminal B, over front contact 96 of relay v, front contact 97 of relay q¹, front contact 98 of relay k, reverse contact 99 of relay k and operating mechanism of signal w¹ to terminal C. 10

In similar manner, the operation of the handle 28 on panel B to clear a westbound signal actuates decoding relay BN¹ or BN² at station B according as the switch is normal or reverse, respectively at station B, and the operation of either of relays BN¹ or BN² results in the energization of relay q², the circuits being similar to those provided for the control of relay q¹. Furthermore, when relay q² is energized an operating circuit is closed for signal w³ or for signal w⁴ according as the indication relay k is energized in its reverse or normal direction. 15

It should be noted that each control code originating at the office conveys information concerning the positions of both the switch lever and the signal lever on the corresponding panel. Moreover, this information is translated at the remote station so that the apparatus at the remote station coincides at all times with the positions of the apparatus on the panel at the control office. One advantage of this arrangement is that only one control code is necessary to change from any condition of apparatus at the remote station to any other condition and a consequent saving is 25 effected in the total length of time during which the line circuit is in use.

In order to inform the operator concerning the condition of the devices at each remote station, I provide each panel with indicating devices, here 40 shown as electric lamps which are controlled in accordance with the positions of the devices at the remote station. For accomplishing the control of these indication devices, I utilize indication codes similar to the control codes previously described and transmitted from the field stations to the control office. These codes consist of code elements of different frequencies and in order to obviate the necessity of a plurality of alternators similar to X, Y and Z at each remote station, I 45 utilize an additional line wire 2 extending from the office to each remote station. The alternators X, Y and Z are all constantly connected across the line wires 2 and 3 at the office, one of the relays AG^X, AG^Y or AG^Z being included in 50 series with each alternator and tuned to resonance at the frequency of the current supplied by the corresponding alternator. For example, relay AG^X is included in the series with alternator X across line wires 2 and 3 and is tuned 55 to resonance by some suitable means, such as a reactor 153 and a condenser 154.

For the purpose of operating the relays AG^X, AG^Y and AG^Z selectively, from any remote station, I provide each such remote station with a 60 plurality of delivery magnets, each of which is arranged when energized to connect across line wires 2 and 3 at the remote station a shunt path which is tuned to resonance at the frequency of the current delivered by a particular one of the 70 alternators at the dispatcher's office.

Referring particularly to Fig. 2, it will be seen that the delivery magnets BD^X, BD^Y and BD^Z at station B are each effective when energized to connect across wires 2 and 3 a tuned path design- 75

nated by the reference character *d* with a distinguishing exponent and each including a condenser 121 and a reactor 122. The tuned paths *d* are separately tuned to resonance at the frequencies of the current supplied by alternators X, Y and Z and it follows when delivery magnet BD^X at station Y is energized, relay AG^X at the office becomes energized. Similarly, the energization of delivery magnet BD^Y at station B picks up relay AG^Y at the office and the energization of relay BD^Z at station B picks up relay AG^Z at the office. The delivery magnets at station B are energized in definite sequences by means of a stepping contactor P^B similar to the stepping contactor at the office except that in the present embodiment the stepping contactor P^B has an additional segment 119 so that indication codes are made up of seven code elements instead of six code elements as is the case with control codes. This additional code element is introduced into the indication codes for the purpose of conveying certain information to the office which could not be conveyed with an indication code of six code elements.

The delivery of indication codes to the office from station B is initiated by the reversal of the master relay J^B which normally occupies the normal position in which it is illustrated in the drawings. The master relay J^B is controlled by a plurality of polarized indication relays each designated by the reference character *r* with a distinguishing exponent. The indication relays *r*¹ and *r*² are controlled in accordance with the position of switch 50 at station B. Indication relays *r*³ and *r*⁴ are associated with the indication of the positions of the signals at station B. Indication relays *r*⁵ and *r*⁶ are controlled in part by the track relay *v* at station B and are utilized to inform the operator when a train, having occupied section *a*—*b*, leaves this section.

Since indication codes can originate at any one of a number of stations, it is manifest that some provision must be made for preventing interference between indication codes originating at different stations. For this purpose, I have provided checking and locking apparatus at each remote station which utilizes the common wire 3 and an additional wire 4 which extends between remote stations. Since this wire 4 is used for only checking and locking between remote stations, it is not necessary to continue this wire to the control office. The checking and locking system illustrated in the drawings is similar to the checking and locking system described and claimed in my co-pending application Serial No. 362,948, referred to hereinbefore. For this purpose station B is provided with a sectionalizing relay S^B, a line relay R^B, a motor relay M^B, a delay relay K^B, and an additional relay T^B, and each of the other remote stations is provided with similar apparatus. Each sectionalizing relay S is normally de-energized and under these conditions, each line relay is connected in series with line wire 4 over a back contact 105 of the associated sectionalizing relay and a battery 104 so that the line relays are all normally energized. Relay T^B is normally de-energized and relays M^B and K^B are also normally de-energized.

When the master relay J^B becomes energized in the reverse direction, the checking and locking apparatus at station B is set into operation. At the conclusion of this checking and locking operation, if relay F^B becomes energized, the transmitting equipment is actuated to deliver a code to the line wires 2 and 3.

I will now describe in detail the operation of the checking and locking apparatus. When relay J^B becomes energized in the reverse direction, the sectionalizing relay S^B picks up, the circuit for this relay passing from terminal B, over front contact 100 of relay R^B, back contact 101 of delay relay K^B, winding of relay S^B and reverse contact 102—102^b of master relay J^B to terminal C. It should be pointed out that relay S^B can become energized only if the line is clear, that is, if no other remote station is delivering a code to the line circuit, because under these conditions, as will be described hereinafter, the normally closed line circuit including line wires 3 and 4 is open and relay R^B is de-energized so that the circuit just traced is open. Furthermore, the closing of relay S^B insures that the line has been cleared for a definite interval of time because when relay R^B becomes de-energized, relay K^B is energized and this relay is slow releasing and holds its back contact open to prevent closing of the circuit for relay S^B for a brief interval of time after relay R^B again becomes energized. When relay S^B becomes energized, thus insuring that the line circuit is clear and has been clear for a definite time interval, the opening of back contact 105 of relay S^B disconnects line wire 4 to all stations more remote from the office than station B. At the same time, however, a local circuit is completed for relay R^B over front contact 105 of relay S^B and back contact 109 of relay T^B. The closing of relay S^B also completes a circuit for relay T^B which now picks up, this circuit passing from terminal B, over front contact 100 of relay R^B, back contact 101 of relay K^B, winding of relay T^B and front contact 103 of relay S^B to terminal C. When relay T^B picks up it interrupts, at back contact 109, the circuit for relay R^B so that the latter relay releases. When relay R^B closes its back contact 100, the operating circuit for relay K^B is closed and this relay picks up. The closing of relay K^B interrupts the circuits for relays T^B and S^B and completes a snubbing or holding circuit for these two relays in series which may be traced from terminal C over front contact 103 of relay S^B, winding of relay T^B, winding of relay S^B and reverse contact 102—102^b of relay J^B back to terminal C. Due to this snubbing circuit, relay S^B holds its front contacts closed, but relay T^B is quick-acting and closes its back contact 109. When this happens, relay R^B picks up provided the line is clear, and a circuit is then closed for the motor relay M^B from terminal B, over front contact 100 of relay R^B, front contact 101 of relay K^B (now de-energized but holding due to its slow-releasing characteristics), winding of relay M^B and front contact 106 of relay S^B to terminal C. Relay M^B therefore becomes energized and completes a stick circuit for relay S^B from terminal B, over front contact 108 of relay M^B, winding of relay S^B and reverse contacts 102—102^b of relay J^B to terminal C. Relay S^B therefore remains in its energized condition. Furthermore, a stick circuit is now closed for relay M^B including its own front contact 107 and front contact 106 of relay S^B. The closing of the motor relay M^B also picks up relay T^B over front contact 108 of relay M^B and front contact 103 of relay T^B, so that relay T^B opens its back contact 109 and de-energizes relay R^B. Relay R^B therefore opens and holds relay K^B energized, and the apparatus remains in this condition during the transmission of a code. It will be noted that relay M^B does not become energized unless relay R^B is ener-

gized, thereby indicating that the line is clear in advance, and unless relay S^B is energized, thereby indicating that the line in the rear of station B is locked out. When motor relay M^B is energized a circuit is completed for stepping magnet F^B of stepping contactor P^B from terminal B, over front contact 111 of relay M^B , winding of stepping magnet F^B , back contact 112 of relay J^B and reverse magnet 102-102^b of master relay 10 J^B to terminal C. The transmitting apparatus is then set into operation to deliver an indication code to the line wires 2 and 3.

In explaining the operation of the indication apparatus, I will assume that all parts of the apparatus occupy the positions in which they are shown in the drawings and that switch 50 at station B is moved to its reverse position. When this operation of the switch commences, relay k becomes de-energized and current then flows 15 from terminal B, over back contact 113 of relay k , thence through winding 114 of relay r^1 and winding 115 of relay r^2 in parallel to terminal C. Relay r^1 is thus operated to its reverse position and relay r^2 is operated to its normal position. 20 When the switch 50 attains its full reverse position, relay k becomes energized in the reverse direction and relay J^B is then reversed by the closing of a starting circuit which may be traced from terminal B, over front contact 113 of relay k , reverse contact 116-116^b of relay r^1 , winding 117 25 of relay r^2 and winding 118 of relay J^B to terminal C. The closing of this circuit restores relay r^2 to its reverse position and operates relay J^B to its reverse position. This operation of relay 30 J^B initiates the checking and locking operation previously described, and if the line 4 is clear, as will be the case if no other remote station is transmitting an indication code, relay F^B becomes energized. When this happens, current 35 flows from terminal B, over front contact 120 of magnet F^B , contact 33-35 of stepping contactor P^B and winding of delivery magnet BD^Z to terminal C. The delivery magnet BD^Z therefore becomes energized to connect the tuned path 40 45 d^Z across line wires 2 and 3, thereby picking up relay AG^Z at the office. Another result of the closing of magnet F^B is to energize relay i^B . The closing of front contact 133 of relay i^B picks up relay j^B , thereby opening, at back contact 112, the circuit for magnet F^B , which releases and advances the stepping contactor P^B to the next position. The operation continues in a manner similar to that described in connection with the apparatus at the office, each position of the stepping contactor producing a distinctive code element, the sequence of these elements being determined by the connections of the delivery magnets with the segments of the stepping contactor. The first four elements of the code are the same 50 55 60 for all indication codes originating at the same station, and are utilized for selecting the corresponding panel at the office. The fifth element of the code, however, is controlled by relay r^6 in accordance with the condition of the track section a-b. As shown in the drawings, relay r^6 occupies its normal position with contacts 123-123^a closed so that when contact 33-39 of stepping contactor P^B is closed, the delivery magnet BD^Y is energized to pick up relay AG^Y at 65 70 75 the office for the fifth element of the code. Similarly, the sixth element of the code is controlled in accordance with the positions of the signals at station B, and since these signals are all at stop, relay r^4 as hereinafter explained will have been reversed, closing contacts 124-124^b to cause

segment 40 of the stepping contactor to be connected with delivery magnet BD^Y so that the sixth element of the code picks up relay AG^Y at the office. The seventh element of the indication code is controlled in accordance with the position of the switch and in the present instance, segment 119 is connected, over reverse contact 125-125^b of relay r^2 , front contact 126 of relay k , and reverse contact 127 of relay k , with delivery magnet BD^Y . During the seventh element of the code, therefore, magnet BD^Y becomes energized to pick up relay AG^Y at the office. It should be noted that when delivery magnet BD^Y is energized during this last element of the code, winding 128 of relay r^1 is also energized thereby restoring 15 relay r^1 to its normal position. The relay r^1 therefore serves to store the indication initiated by the movement of the relay k in response to a reversal of the switch, by maintaining the starting circuit for relay J^B closed until the corresponding indication has actually been delivered to the office. At the conclusion of the seventh element of the code, the contact 33-41 of contactor P^B is closed, and when magnet F^B next becomes energized, current is supplied to winding 134 of relay J^B , 20 25 thereby restoring this relay to its normal position. When this happens, the stepping magnet F^B is energized, thereby advancing the spider 33 one step to close contact 33-35 and places the apparatus in condition to start the delivery of 30 another indication code. Furthermore, the opening of contact 102-102^b of master relay J^B opens the stick circuit for relay S^B , which thereupon releases and de-energizes relays M^B and T^B . The de-energization of relay S^B restores the normal line circuit, and if the line is clear, relay R^B becomes energized and drops relay K^B to restore the apparatus to its normal condition. 35

Referring now to Fig. 1, it will be observed that the relays AG^X , AG^Y and AG^Z control a relay A^H 40 which is energized when any one of the three relays just mentioned, is energized. The control office is also provided with a plurality of decoding relays AN^1 , AN^2 , etc., each of which is similar to the decoding relays located at the remote stations, except that the decoding relays at the office, being designed for operation upon indication codes having seven elements per code, each have seven positions in each of the driving disks for magnetic slugs 16. For purposes of economy I prefer to use for each item of information received from the remote stations the same final elements 45 50 55 of the indication codes originating at all stations. For example, the indication "switch reverse" will be made up of seven code elements the first four of which will be distinctive for each station, the last three of which will be the same for all stations. By this means I can utilize a single decoding relay responsive to all indication codes which terminate in the three code elements 60 65 70 75 corresponding to a "switch reverse" code and by employing a separate decoding relay for each panel, I can distinguish at which station the indication code originates. As shown in Fig. 1 a decoding relay B^a is arranged to operate in response to any indication code originating at station B, and when contact 68-70 of this relay closes, an auxiliary relay f becomes energized. Since relay B^a is adjusted to respond to any indication code originating from station B, this relay becomes energized in response to the indication code just described. This indication code also actuates decoding relay AN^1 . Since relay f is now energized, the closing of contact 68-70 of relay AN^1 completes a circuit from terminal B, through 75

winding 135 of relay AL², winding 136 of relay AL¹, front contact 137 of relay f, and contact 68-70 of relay AN¹ to terminal C. The closing of this circuit has no effect upon relay AL², but relay AL¹ becomes energized in the reverse direction and current then flows from terminal B, over normal contact 138-138^a of relay AL², reverse contact 139-139^b of relay AL¹, and lamp 30 to terminal C. Lamp 30 is therefore lighted, and since lamp 29 was extinguished by the reversal of relay AL¹, the lighting of lamp 30 gives the operator a positive indication that the switch at station B now occupies its reverse position.

If now the switch 50 at station B is restored to its normal position, relay k becomes de-energized at the beginning of this movement, thereby energizing winding 114 of relay r¹ and winding 115 of relay r² and causing relay r¹ to be operated to reverse and relay r² to be operated to normal. When the switch has attained its full normal position, the consequent energization of relay k completes a circuit from terminal B, over front contact 113 of relay k, reverse contact 116-116^b of relay r¹, winding 117 of relay r², and winding 118 of relay JB to terminal C. Relays r² and JB are then operated to reverse and this operation of the master relay JB initiates the checking and locking operation described hereinbefore. At the conclusion of this operation the stepping magnet FB becomes energized and the apparatus then proceeds to deliver to the office an indication code in the manner described hereinbefore, with the exception that the seventh element of this code is produced by operation of delivery magnet BD^x, the circuit for the delivery magnet under these conditions passing from terminal B, over front contact 120 of stepping magnet FB, contact 33-119 of contactor PB, contact 125-125^b of relay r², front contact 126 of relay k, normal contact 127 of relay k, and winding of delivery magnet BD^x to terminal C. It will be noted that the circuit just traced is provided with a branch which passes from reverse contact 125-125^b of relay r², through winding 128 of relay r¹ to terminal C. The relay r¹ is therefore restored to normal, opening the starting circuit so that relay JB will be restored to normal at the conclusion of the indication code.

The indication code thus supplied to the office operates relays AG^x, AG^y and AG^z in a definite sequence which results in the actuation of decoding relays B^a and AN². These relays do not operate until the last element of the code is received and when this happens, relay f becomes energized and a circuit is then completed from terminal B, through winding 135 of relay AL², winding 140 of relay AL¹, front contact 141 of relay f, and contact 68-70 of relay AN² to terminal C. Relays AL¹ and AL² are thus both energized in the normal directions, thereby extinguishing lamp 30 on panel B and completing a circuit for lamp 29 from terminal B, over normal contact 138-138^a of relay AL², normal contact 139-139^b of relay AL¹ and lamp 29 to terminal C. The lighting of lamp 29 therefore informs the operator that the switch at station B occupies its normal position.

As will be explained below, an indication code can be initiated at station B by other means than by the operation of switch 50, as for example, when a signal relay q becomes energized or released, or when the track relay v becomes energized. Each indication code, however, conveys complete information to the office concerning the condition of all of the apparatus at the station

where the code originated. If an indication code is delivered from station B when switch 50 is unlocked, that is, when the switch does not occupy either extreme position, the indication relay k will be de-energized, operating relay r¹ to reverse, and operating relay r² to normal to close contact 125 to the left. Under these conditions, the seventh element of the code will be obtained by energizing the delivery magnet BD^x. The indication code thus delivered to the office energizes relays B^a and AN², whereupon a circuit is completed from terminal B, through winding 142 of relay AL², front contact 143 of relay f and contact 68-70 of relay AN³ to terminal C. Relay AL² is then energized in the reverse direction and the circuits for both lamps 29 and 30 are broken at normal contact 138-138^a of relay AL². Under these conditions, both lamps 29 and 30 remain extinguished, thereby informing the operator that the switch at station B is unlocked.

I will now assume that signal relay q¹ is energized to clear an eastbound signal. The energization of this relay completes a circuit from terminal B, over back contact 144 of relay q², front contact 129 of relay q¹, winding 130 of relay r⁴, normal contact 131-131^a of relay r³ and winding 118 of relay JB to terminal C. The consequent reversal of relay JB initiates the delivery of an indication code from station B, and relay r⁴ is at the same time operated to normal to close contact 124 to the left, so that the sixth element of the code is produced by energizing relay BD^x over a circuit which extends from terminal B, contact 120 of relay FB, stepping contacts 33-40, left-hand contact 124 of relay r⁴, asymmetric unit 155, relay BD^x to terminal C. Relay r³ is energized in the reverse direction over a branch of this circuit which extends from the upper terminal of asymmetric unit 155 through winding 132 of relay r³ to terminal C. Asymmetric unit 155 serves to prevent the flow of current in the reverse direction in the branch of this circuit leading to relay BD^x, and it follows therefore that relay r³ is reversed to open the starting circuit for relay JB when stepping contacts 33-40 close, but does not become energized when relay BD^x is energized on other steps of the code. When this code is received at the office, relays AN⁴ and B^a are energized and relay AL² is then energized in the normal direction to close contact 145-145^a. Lamp 31 is then extinguished and lamp 32 is lighted, thereby informing the operator that a signal is cleared at station B. The same indication would have been received had relay q² been energized at station B so that the indication does not inform the operator which signal is clear. By observing the position of handle 28, however, he can determine the direction of traffic which has been set up at the station and by observing which of the lamps 29 or 30 is lighted, he can determine the position of the switch and hence the particular one of the signals which is clear. It should be noted that in the indication code just described, the seventh element of the code is controlled in accordance with the position of the switch, and the decoding relays at the office are preferably constructed in such manner that one of the relays AN¹, AN² or AN³ will be actuated simultaneously with relay AN⁴ depending upon the position of the switch at the station.

When relay q¹ is de-energized to return the signal at station B to its stop position, a circuit is completed from terminal B, back contact 144 of relay q², back contact 129 of relay q¹, the reverse winding of relay r⁴, reverse contact 125 to the left. Under these conditions, the seventh element of the code will be obtained by energizing the delivery magnet BD^x. The indication code thus delivered to the office energizes relays B^a and AN², whereupon a circuit is completed from terminal B, through winding 142 of relay AL², front contact 143 of relay f and contact 68-70 of relay AN³ to terminal C. Relay AL² is then energized in the reverse direction and the circuits for both lamps 29 and 30 are broken at normal contact 138-138^a of relay AL². Under these conditions, both lamps 29 and 30 remain extinguished, thereby informing the operator that the switch at station B is unlocked.

- 131—131^b of relay r^3 and winding 118 of relay J^B to terminal C. The consequent reversal of relays J^B and r^4 initiates the delivery of an indication code in which the sixth element is produced 5 by energization of delivery magnet BD^Y over a circuit including stepping contacts 33—40 similar to that already traced but which includes reverse contacts 124—124^b of relay r^4 . Relay r^3 is energized in the normal direction over a branch 10 of this circuit to again close contacts 131—131^a and to open the starting circuit. When this code is received at the dispatcher's office, it energizes relays AN^5 and B^n . In addition one of the relays AN^1 , AN^2 or AN^3 is actuated, depending 15 upon the position of the switch at the station. When relays AN^5 and B^n are energized, relay AL^3 is energized in the reverse direction by a circuit which will be obvious from the drawings, and lamp 32 is then extinguished and lamp 31 20 is lighted to indicate to the operator that all signals at station B are at stop. It will be noted that during the delivery of the sixth element of the indication code from station B, one winding or the other of relay r^3 is in each case energized 25 in parallel with the delivery magnet and is energized by current supplied over contacts 33—40 so that this relay is put into a position to open the starting circuit for the indication code which is delivered.
- 30 The track relay v controls relays r^5 and r^6 in a manner similar to the control of relays r^1 and r^2 by relay k except that there is, of course, no polarized contact on relay v entering into this control. It will be obvious, without tracing the 35 operation in detail, that when relay r^6 is normal, the fifth element of codes originating from station B, is produced by energizing delivery magnet BD^Y . If relay v is de-energized, however, relay r^6 becomes reversed, and then when relay 40 v again becomes energized, as upon the departure of a train from section $a-b$, relays r^6 and J^B are operated to reverse and a code is delivered from station B which has its fifth element produced by energization of magnet BD^X , by the 45 closing of a circuit which includes stepping contacts 33—39 and contacts 123—123^b of relay r^6 . Relay r^6 is energized in the normal direction over a branch circuit when the stepping contacts 33—39 become closed, while relay r^6 is restored 50 to normal at the end of the code when stepping contacts 33—41 become closed. This indication code energizes relays AN^6 and B^n at the office. It is customary in usual practice to indicate the 55 passage of trains through the portion of track controlled by apparatus embodying my invention on a graphic recorder, rather than by lamps on the control panel. I therefore provide a graphic recorder having a magnet 146 controlling a pen 147 which operates upon a moving record sheet 148. When relays B^n and AN^6 are energized, the magnet 146 on the graphic recorder is energized over front contact 149 of relay f , and contact 60 68—70 of relay AN^6 , to record upon sheet 148 the departure of the train from section $a-b$.
- 65 It will therefore be apparent that with apparatus embodying my invention, the operator at the dispatcher's office has before him at all times complete information of the condition of all apparatus at each remote station. This information 70 is all conveyed by means of codes which are distinguished, not by the lengths of code elements, and not by the number of impulses in different code elements, but by the sequence in which code elements of different characters are delivered to a line circuit. One advantage of

this feature is that all code elements may be of equal lengths and the length of a code element may be very short, the only requirement being that each code element be prolonged for a time sufficient to operate the relay which is selectively responsive to that code element. In actual practice, I have discovered that relays selectively responsive to the frequency of the currents utilized for code elements may be made to operate reliably upon code elements of the order of $\frac{1}{6}$ of a second duration. It is manifest that with a system operating upon this principle, the time required for each code is comparatively small and a large number of indications may therefore be handled over a single pair of line wires in a comparatively short time.

It should be pointed out that while I have, for purposes of illustration, shown and described one form of coding relay which may be utilized in practicing my invention, this particular form of relay is not essential but its function may be performed by any equivalent apparatus. In similar manner, I do not wish to limit my invention to the use of a stepping contactor of the type here described, as any other step-by-step device could be substituted for this mechanism.

It is also apparent that the actual control of the devices at the remote station by the decoding relays, and the specific control of the indication apparatus by the decoding relays at the control office may be modified to meet local conditions, and that the circuits here disclosed are only shown by way of illustration.

In describing my invention, I have assumed that four elements of the code are utilized to accomplish the station selection and panel selection. By using four elements for this purpose each of which elements may be of any one of three frequencies, the system can be utilized with a total of 81 remote stations and a corresponding number of panels. It is manifest, however, that by changing the number of code elements, or by changing the number of frequencies available for each element, a greater or smaller number of stations and panels may be controlled over a single pair of line wires.

Although I have herein shown and described only one form of remote controlling apparatus embodying my invention, it is understood that various changes and modifications may be made therein within the scope of the appended claims without departing from the spirit and scope of my invention.

Having thus described my invention, what I claim is:

1. In combination, a plurality of sources of currents of different characters, a plurality of devices each selectively responsive to a different one of such currents, means for repeatedly supplying all of said devices with current from selected ones of said sources in a predetermined sequence, receiving apparatus comprising a plurality of circuits one controlled by each said device, a plurality of magnets, including one in each of said circuits, and a contact controlled by said magnets, said contact being selectively responsive to the sequence in which said circuits are controlled.

2. In combination, a plurality of sources of currents of different characters, a plurality of devices each selectively responsive to a different one of such currents, means for repeatedly supplying all of said devices with current from selected ones of said sources in a predetermined sequence, receiving apparatus comprising a plu-

rality of magnets one controlled by each of said devices, and a contact controlled by said magnets and selectively responsive to the sequence of operation of said magnets.

5 3. In combination with a movable device, a plurality of sources of periodic currents of different frequencies, a plurality of selecting relays each tuned to resonance at a different one of said frequencies, means controlled by said device for 10 connecting said selecting relays with selected ones of said sources in a predetermined sequence which depends upon the position of said device, a slow-acting relay arranged to be energized when any one of said selecting relays is energized, 15 and indication means controlled jointly by said selecting relays and by said slow acting relay and selectively responsive to the sequence of operation of said selecting relays.

4. In combination with a line circuit, a plurality of alternators delivering alternating currents of different frequencies, means for successively connecting selected ones of said alternators with said line circuit in a predetermined sequence, a plurality of frequency responsive line 25 relays connected to said line circuit including one responsive to the frequency of each alternator, a decoding relay having a plurality of magnets one for each said alternator and each arranged to be energized when the corresponding line relay is energized, and a contact controlled by the decoding relay and selectively responsive to the sequence of energization of said magnets.

5. In combination, a plurality of relays, means for energizing selected ones of said relays in a 35 predetermined sequence, a device comprising a plurality of magnets, one for each such relay, means for energizing each such magnet when the associated relay is energized, and a contact controlled by said magnets and selectively responsive to the sequence of energization of such magnets.

40 6. In combination, a plurality of relays, means for energizing selected ones of said relays in a selected sequence, a movable member biased to an initial position, means including drive magnets and effective upon each energization of any one of said relays in said sequence for moving said member away from such initial position, means for holding said member between such 45 movements, and a contact controlled by said member.

55 7. In combination with transmitting apparatus for delivering a code made up of a plurality of successive code elements of at least two different characters in a predetermined sequence, a plurality of relays one for each character of code element, means for energizing each said relay when a code element of corresponding character is transmitted by said apparatus, a movable 60 member biased to an initial position, means including drive magnets and effective when said relays are energized in said predetermined sequence to progressively move said member step-by-step away from said initial position, said 65 member being moved one step for each element of the code, and a contact controlled by said member and arranged to be closed at the conclusion of such code.

8. In combination, a plurality of stepping magnets, a holding magnet, a rotatable shaft having a plurality of non-magnetic disks, one for each magnet, a plurality of magnetic slugs placed in selected positions in said disks and under the control of the associated magnets, means for 70 selectively energizing said magnets to attract the

magnetic slugs one at a time in a predetermined order to cause step-by-step rotation of said shaft, and a contact controlled by said shaft.

9. In combination, an electromagnet having spaced pole pieces, a movable lever having two magnetizable arms separated by an air gap and biased to one position but movable under the attraction of said electromagnet to a position in which said arms are adjacent said pole pieces respectively, a movable member having a magnetic slug located in said air gap and adapted to be held therein magnetically when said lever is moved in response to the energization of the electromagnet, and a contact controlled by said movable member.

10 15 10. In combination, a plurality of stepping magnets, a holding magnet, a movable member biased to an initial position, means for successively energizing selected ones of said stepping magnets in a predetermined sequence, means controlled by such stepping magnets and effective when the magnets are energized in said sequence for causing step-by-step movement of said member away from said initial position, means for energizing said holding magnet during the intervals between successive step-by-step movements of the member, means for preventing the return of said member to its initial position when said holding magnet is energized, and a contact controlled by said member.

20 25 30 35 40 11. In combination, a movable device, a source of code elements of different characters, a plurality of receiving devices one responsive to each character of code element, means for repeatedly supplying all of said receiving devices with selected ones of such code elements in different sequences depending upon the position of said movable device, and code responsive means controlled by said receiving devices and responsive selectively in accordance with the sequence of operation of such receiving devices.

45 12. In combination, a stepping contactor comprising a series of contacts arranged to be closed in succession, a plurality of sources of currents of different characters, a line circuit, a plurality of delivery magnets one for each said source and each arranged when energized to connect the associated source with said line circuit, a plurality of manually operable levers, means set into operation upon a movement of any lever for operating said stepping contactor, and means operating when any contact of said series is closed to energize for a measured interval of time a selected one of such delivery magnets depending upon which lever was operated and upon the 50 55 position such lever occupies.

13. In combination with a line circuit, a plurality of sources of periodic current of different frequencies, means for supplying said line circuit with successive code elements each made up of an impulse of current of a selected one of said frequencies, a plurality of relays all receiving energy from said line circuit and each arranged to close its contacts only when supplied with current of a different one of said frequencies, and a 60 65 decoding device controlled jointly by said relays and selectively responsive to the sequence of operation of such relays.

70 75 14. In combination with a line circuit connecting a plurality of remote stations and a control station, a plurality of devices at each station, a plurality of panels at the control station, means set into operation upon a change in the condition of any device at a remote station for supplying the line circuit with a code made up of

- code elements of equal lengths but different characters in a distinctive sequence, code responsive means at the control station for selecting a particular panel in accordance with the character of certain of said code elements, a plurality of indication devices for each panel, and means selectively responsive in accordance with the character of certain other code elements for selecting a particular indication device of said particular panel.
15. In combination with a line circuit connecting a control station and a plurality of remote stations, a plurality of panels at the control station including one for each station each provided with a plurality of manually controlled levers, a plurality of governing devices at each remote station, means set into operation upon a change in the position of any lever at the control station for delivering to the line circuit a code made up of code elements of equal lengths but having different characteristics in a distinctive sequence, including certain elements identifying the panel containing the operated lever and other elements identifying the positions of the levers of said panel, a plurality of relays at each station one such relay at each station responding selectively to each character of code element, and means at each station for selectively controlling the devices at such station in accordance with the sequence of operation of the associated relays.
16. In combination with a line circuit, a plurality of sources of periodic currents of different frequencies, a plurality of delivery contacts one for each said source and each arranged when actuated to connect the associated source with said line circuit, a master relay having normal and reverse positions, a manually controlled lever, means controlled by a reverse contact of said master relay for actuating selected ones of said delivery contacts for equal lengths of time in a predetermined sequence depending upon the position of said lever to deliver a complete code to the line circuit, means controlled by said lever for operating said master relay to its reverse position, and means effective after the completion of said complete code to restore the master relay to its normal position.
17. In combination with an office and a station connected by a pair of line wires, a source of periodic current, a relay, means for connecting said source and said relay in series across said line wires at said office, a normally open conducting path between said line wires at said station tuned to resonance at the frequency of said periodic current, means at said station for at times closing said path, and indication means at said office controlled by said relay.
18. In combination with an office and a station connected by two line wires, a plurality of sources of periodic current of different frequencies, a plurality of relays one for each such source, means for connecting each such source and the associated relay in series across said line wires at said office, a plurality of normally open contacts, a plurality of conducting paths between said line wires at said station, each including one of said contacts and each tuned to resonance at a different one of said frequencies, means at said station for selectively operating said contacts, and indication means at said office controlled by said relays.
19. In combination with an office and a station connected by two line wires, a plurality of sources of periodic current of different frequencies, a plurality of relays one for each such source and the associated relay in series across said line wires at said office, a plurality of normally open contacts, a plurality of conducting paths between said line wires at said station, each including one of said contacts and each tuned to resonance at a different one of said frequencies, means at said station for selectively operating said contacts, and indication means at said office controlled by said relays.
20. In combination, four decoding relays each having a contact arranged to be closed for a brief interval of time when the device is operated, two polarized relays, means for energizing one polarized relay in the normal direction when a first or a second decoding relay is operated, means for energizing said one polarized relay in the reverse direction when a third or a fourth decoding relay is operated, means for energizing said other polarized relay in the normal direction when said first or said third decoding relay is operated, means for energizing said other polarized relay in the reverse direction when said second or said fourth decoding relay is operated, two movable devices, means for operating one said device to one position or another according as said first polarized relay is energized in the normal or reverse position, means for operating the other said device to one position or another according as said second polarized relay is energized in the normal or reverse position, and means for selectively operating said decoding relays to control the positions of both said devices.
21. In combination with a line circuit, transmitting means arranged to deliver to said line circuit code elements of different characters in different sequences, a first group of relays controlled by the code elements delivered to said line circuit and selectively responsive to the character of each said code element, a second group of relays controlled by the relays of said first group and selectively responsive to the sequence of operation thereof, and a third group of relays selectively controlled by the relays of the second group.
22. In combination with a line circuit, transmitting means arranged to deliver to said line circuit code elements of different characters in different sequences, a first group of relays one for each character of code element, a receiver associated with said line circuit including means responsive to a code element of each character for effecting at any point in a sequence the selective operation of a definite one of such relays corresponding to the character of the received element, and a second group of relays controlled by and selectively responsive to the sequence of operation of the relays of said first group.
23. In combination with a line circuit, transmitting means arranged to deliver to said line circuit a series of code elements of different characters in different sequences, a first group of relays one for each character of code element, a receiver associated with said line circuit including means responsive to a code element of each character for effecting at any point in a sequence the selective operation of a definite one of such relays in accordance with the character of the received element, a stepping device provided with a contact, and means controlled by and selectively responsive to the sequence of operation of

the relays of said first group for closing said contact at the end of the series of code elements.

24. In combination with a line circuit, transmitting means arranged to deliver to said line circuit a series of code elements each having a selected one of at least three different characters, a receiver controlled by the code elements delivered to said line circuit and selectively responsive to the character of each code element, stepping means controlled by said receiver, and means governing the operation of said stepping means in accordance with the sequence of the different characters of said code elements.

25. In combination, a line circuit, means for transmitting to said line circuit a code made up of a series of code elements each having a selected one of at least three different characters, receiving means controlled by the code elements delivered to said line circuit and selectively responsive to the character of each element, a three-position movable device, stepping means controlled by said receiving means adapted to operate said device to any one of its three positions in accordance with the character of one element of the code, and means governing the operation of said stepping means in accordance with the sequence in which code elements of different characters occur in said code.

26. In combination, a line circuit, means for transmitting to said line circuit a code made up of a series of code elements each having a selected character, receiving means controlled over said line circuit and adapted to register the character of each of the successive elements of said code, stepping means controlled by said receiving means, means requiring a code having code elements arranged in a definite sequence for operating said stepping means progressively, and means effective upon the progressive operation of said stepping means by a complete code to register said code.

27. Receiving means for codes made up of series of code elements each having a selected character comprising a group of devices each supplied with every element of said codes but each selectively responsive to elements of a different character, and stepping means controlled by said devices and selectively responsive to the particular device which responds during each code element and arranged to be operated progressively through a number of steps corresponding to the number of elements if and only if said devices respond in accordance with a single predetermined sequence.

28. Receiving means for codes made up of series of code elements each consisting of an impulse of current of a selected one of at least three different frequencies, comprising a group of frequency selective relays each supplied with every element of said codes, and registering means controlled by said relays and selectively responsive to the particular relay in said group which responds during each code element only if said relays are operated in a predetermined sequence.

29. A centralized traffic controlling system for railroads comprising an office and a station, two line circuits connecting said office and station, a plurality of sources of currents of different characters at said office, means for connecting said sources with one said line circuit in a predetermined sequence to deliver a code to said station, receiving means at said station selectively responsive to said code, railway traffic governing means at said station selectively controlled by said receiving means, indication means at the

office responsive to the flow of current from said sources in the other said line circuit, and means responsive to traffic conditions at said station for controlling the current in said other circuit.

30. A centralized traffic controlling system for railroads comprising an office and a station, two line circuits connecting said office and station, a plurality of sources of currents of different characters at said office, means for connecting said sources with one said line circuit in a predetermined sequence to deliver a code to said station, receiving means at said station selectively responsive to said code, railway traffic governing means at said station selectively controlled by said receiving means, indication means at the office responsive to the flow of current in the other said line circuit, means for constantly connecting at least one of said sources with said other line circuit, and means responsive to traffic conditions at said station for controlling the current in such other line circuit.

31. A centralized traffic controlling system for railroads comprising an office and a plurality of stations, two line circuits extending from said office to all of said stations, a plurality of sources of currents of different characters at said office, means for connecting said sources with one said circuit in different sequences to transmit distinctive codes to said stations, receiving means at each station selectively responsive to said codes, railway traffic governing means at each station controlled by the associated receiving means, indication means at the office responsive to current flowing in the other said line circuit, means for constantly connecting at least one of said sources with said other circuit, and means at each station controlled by traffic conditions at such station for controlling the current in said other line circuit.

32. A centralized traffic controlling system for railroads comprising an office and a plurality of stations connected by a line circuit, a plurality of levers at said office one for each said station and each having a plurality of control positions, a plurality of current sources at said office, means responsive to a change in the position of any lever for connecting said sources selectively with said line circuit in a sequence which depends upon the particular lever which was operated and for subsequently connecting a particular one of said sources with the line circuit depending upon the position then occupied by such lever to produce an operating impulse, receiving means at each station selectively responsive to said sequence to select the particular station corresponding to the operated lever, a traffic governing device at each station, and means at each station effective when the associated receiving means is actuated to control the corresponding traffic governing device selectively in accordance with the particular source connected with said line circuit during said operating impulse.

33. In combination, a railway system, a central office from which train movements over said system may be directed, a plurality of way stations, a traffic controlling device at each way station, a line circuit connecting said central office and said way stations, and means for distinctively operating said traffic controlling devices over said circuit including code creating mechanism at said central office and code responsive mechanism at said way stations for respectively creating and deciphering codes of which each code comprises a plurality of distinctive frequency impulses in a distinctive order.

34. In combination, a railway system, a central office from which train movements over said system may be directed, a plurality of way stations, a track circuit at each way station, a line circuit connecting said central office and said way stations, and means for distinctively indicating at said central office the occupancies of the various track circuits including code creating and code responsive devices for creating and deciphering codes, each code of which comprises a plurality of distinctive frequency impulses.

35. In combination, a railway system, a central office from which train movements over said system may be directed, a plurality of way stations, a track circuit at each way station, a line circuit connecting said central office and said way stations, and means for distinctively indicating at said central office the occupancies of the various track circuits including code creating and code responsive devices for creating and deciphering codes each code of which comprises a plurality of distinctive frequency impulses given in a distinctive order.

36. A centralized traffic controlling system for railroads comprising an office and a station, two line circuits connecting said office and station, a plurality of sources of current at said office, means at said office for supplying to one said line circuit from said sources a series of code elements each of distinctive character in a predetermined sequence, receiving means at said station selectively responsive to said series, railway traffic governing means at said station selectively controlled by said receiving means, indication means at the office responsive to code signals in the other said line circuit, means for constantly connecting said sources with said other line circuit, and means responsive to traffic conditions at said station for controlling the current in such other line circuit to produce code signals therein.

37. A centralized traffic controlling system for railroads comprising an office and a plurality of stations, two line circuits extending from said office to all of said stations, a plurality of sources of current at said office, means at said office for supplying to one said line circuit from said sources a series of distinctive code elements, receiving means at each station selectively responsive to said series, railway traffic governing means at each station controlled by the associated receiving means, indication means at the office responsive to code signals in the other said line circuit, means for constantly connecting said sources with said other circuit, and means at each station controlled by traffic conditions at such station for controlling the current in said other line circuit to produce code signals therein.

38. A centralized traffic controlling system for railroads comprising an office and a station, two line circuits connecting said office and station, a plurality of sources of current at said office, means at said office for supplying from said sources to one said line circuit a series of code elements arranged in predetermined sequence, receiving means at said station selectively responsive to said series, railway traffic governing means at said station selectively controlled by said receiving means, indication means at the office, contact mechanism controlled by said traffic governing means; and means including the other said line circuit, said contact mechanism, and said sources for controlling said indication means.

39. In a centralized traffic controlling system for railroads, an office and a plurality of stations

connected by a line circuit, a plurality of sources of current at said office, a plurality of control panels at said office each provided with a movable lever, means controlled from any panel for transmitting a code produced by connecting at least one of said sources with said line circuit to create a sequence of code elements each of a particular character of which sequence one part is controlled in accordance with the corresponding panel and another part is controlled by the position of the lever associated with said panel, a traffic governing device at each said station, receiving means at each station selectively responsive to said one part of said sequence, means at each station effective when the associated receiving means is selected to control the traffic governing device at such station in accordance with said other part of the sequence, and other means including at least one of said sources for indicating the position of each said traffic governing device on the corresponding office panel.

40. In combination with a plurality of groups of movable devices, code transmitting means for producing a series of code elements each comprising an impulse of current of determinable character, means for initiating operation of said code transmitting means from any of said groups, means for determining the character of current comprising certain elements of each said code in accordance with the group from which the code was initiated, and means responsive to the condition of the devices in such group for determining the character of current comprising the remaining elements of said code, and receiving means responsive to the character of the current comprising each of the elements of said code.

41. Code transmitting apparatus comprising a plurality of independently operable starting devices, a series of code sending relays one for each said starting device, means for operating the first code sending relay in said series which has its starting device operated, means effective when a code sending relay is operated to transmit a series of code elements arranged in a definite sequence and each comprising an impulse of a selected one of a plurality of characters of current, and means effective upon the completion of said series of code elements to restore the operated code sending relay to its original condition and to operate the next code sending relay in said series which has its corresponding starting device operated.

42. In a remote control system of the code type, transmitting apparatus for delivering codes made up of selecting elements and function elements each comprising an impulse of a selected one of a plurality of characters of current, a plurality of groups of movable devices, a code sending relay for each said group, means for selectively energizing any one of said code sending relays and for preventing the energization of any other code sending relay while the selected relay is energized, means controlled by the energized relay for initiating the operation of said transmitting apparatus and for determining the character of each selecting element of the resulting code, means controlled by the energized relay and by the devices of the associated group for determining the characters of the function elements of said resulting code, and receiving means selectively responsive to each element of each code delivered by said transmitting apparatus.

43. A remote control system comprising an office and a plurality of stations connected by a line wire, a plurality of sources of periodic currents of different frequencies at said office, a dis-

tributor comprising a series of contacts and means for closing said contacts in a predetermined order, means including the contacts of said distributor for connecting said sources with said line wire in different sequences to produce different code signals, receiving means at each station selectively responsive to currents of said different frequencies, and a selector at each station controlled by the receiving means at that station and individually responsive to a particular one of said code signals.

44. A remote control system comprising an office and a plurality of stations connected by a line wire, a plurality of sources of periodic currents of different frequencies at said office, a distributor comprising a series of contacts and means for closing said contacts in a predetermined order, means including the contacts of said distributor for connecting said sources with said line wire selectively to produce different code signals, each comprising a sequence of frequencies individual to a particular station, receiving means at each station each including a frequency responsive relay for each frequency of the code signal individual to such station, and a selector at each station controlled by the associated receiving means and selectively responsive to the code signal individual to such station.

45. A remote control system comprising an office and a plurality of stations connected by a line wire, a plurality of sources of periodic current of different frequencies at said office, a distributor at the office comprising a series of contacts closed in a predetermined order, means controlled by the contacts of said distributor for connecting said sources with said line wire selectively to produce different signals one for each said station, a selector at each said station individually responsive to the signal for that station, a device at each station and a control lever at the office for each said device, and means responsive to the movement of one of said levers for actuating the station device corresponding to the operated lever in accordance with the position then occupied by such lever when the distributor has been operated to a predetermined position provided only the selector at the station where the device is located has responded to the signal for such station.

50 46. In a remote control system comprising an office and a plurality of stations connected by a line wire, a movable device at each station, a control lever at the office for each device, means set into operation by a change in the position of any lever for delivering to the line wire a code comprising a sequence of periodic currents of selected frequencies, a frequency responsive relay for each frequency of each such code at each station, and means at each station controlled by the associated frequency responsive relays for selectively controlling the device at such station when the associated relays are actuated in a sequence which is in accordance with a particular one of said codes.

65 47. A centralized traffic controlling system for railroads comprising an office and a plurality of stations connected by a line wire, a railway traffic governing device at each station, a control lever at the office for each device, means set into operation by a change in the position of any lever for delivering to the line wire a code comprising periodic currents of selected frequencies, a frequency responsive relay for each frequency of each such code at each station, receiving means at each station selected only when

the associated relays are actuated in accordance with a particular one of said codes, and means at each station controlled by the associated receiving means when selected to control the device at such station in accordance with the position then occupied by the corresponding lever.

5 48. In a remote control system including a line circuit, code transmitting apparatus comprising a movable lever, a master relay normally occupying one position, means controlled by said lever for operating said master relay to a different position, a plurality of sources of periodic currents of different frequencies, and a distributor effective when said relay occupies said different position to connect said sources with said line wire selectively to produce a distinctive signal the character of which depends in part upon the position then occupied by said lever.

49. In a remote control system including a line circuit, code transmitting apparatus comprising a plurality of movable levers, a master relay normally occupying one position, means controlled by any said lever for operating said master relay to a different position, a plurality of sources of periodic currents of different frequencies, and a distributor effective when said relay occupies said different position to connect said sources with said line wire selectively to produce a distinctive signal the character of which depends in part upon the particular lever which caused the operation of said master relay and in part upon the position of such particular lever.

50 50. A remote control system comprising an office and a plurality of stations connected by a line wire, a plurality of sources of periodic current of different frequencies at the office, means at the office for connecting said sources to the line wire selectively to produce different signals one for each station, a selector at each station selectively responsive to an individual one of said signals, a manually controlled communication channel rendered available from the office to a particular station when the selector at such station is actuated, and means for transmitting a message over said channel to perform a selected operation at such station.

55 51. A centralized traffic controlling system for railroads comprising an office and a plurality of stations connected by a plurality of frequency responsive communication channels all including the same line wire, a distributor operable through a cycle and effective during each cycle to close said channels selectively to produce different signals in said line wire, selector means for each station selectively responsive to said signals located at said office, a track section at each station, means for operating said distributor, means effective when any said section becomes occupied to close a particular one of said channels during the operation of said distributor, and frequency responsive means at the office responsive to the closing of said particular channel provided only the selector associated with the corresponding station has been operated for indicating the occupancy of the track circuit at such station.

60 52. A centralized traffic controlling system for railroads comprising an office and a plurality of stations connected by a plurality of frequency selective communication channels all including the same line wire, a plurality of sources of periodic currents of different frequencies at the office, means at the office for selectively delivering currents from said sources to said channels in different sequences to produce different code signals, a plurality of relays at each station, one

in each said channel, and a selector at each station controlled by the relays at such station and operating only when said relays are actuated in a sequence corresponding to a particular one of said code signals individual to such station.

53. In combination, a railway system, a central office from which train movements over said system may be directed, a plurality of way stations, a traffic controlling device at each way station, a line circuit connecting said central office and said way stations, and means for distinctively operating said traffic controlling devices over said circuit including code creating mechanism at said central office and code responsive mechanism at 10 said way stations for respectively creating and deciphering codes of which each code comprises a plurality of distinctive frequency impulses.

54. In power operated railway switch and signal mechanism, a control panel comprising a 20 panel board with the track layout indicated on the face thereof, a plurality of manually movable control members corresponding to the several track switches to be controlled, each control member comprising a manually oscillatable 25 switching device having a route indicating member located on the face of the panel to cooperate with the track layout indicated thereon, and an electric switch mechanism carried by the panel and comprising a contact attached to said indicating member and movable therewith.

55. In power operated railway switch mechanism, a control panel comprising a panel board with the track layout indicated on the face thereof, a plurality of manually movable control members corresponding to the several track switches to be controlled, each control member comprising a manually oscillatable switching device having a route indicating member movable on the 40 face of the panel to cooperate with the track layout indicated thereon, and an electric switch mechanism mounted on the panel and comprising a contact member attached to said indicating member.

56. The combination, with a railway track switch and power mechanism for operating said switch, of a track model comprising a panel having a graphic representation of the main track and the siding track connected by said track switch, a miniature track switch located on the 50 front of said panel and movable in a plane parallel to the panel and by its position with respect to said graphic representation representing the position to be assumed by the switch, a handle attached directly to said miniature track switch and adapted to be grasped by the operator for moving said miniature switch, a movable contact driven by said handle, a fixed contact cooperating with said movable contact, and means controlled 55 by said movable contact and said fixed contact for governing said power mechanism.

57. In combination with a railway traffic governing device having an operating circuit, a rotatable member, a contact carried by said member, a fixed contact cooperating with the contact on said member to control the operating circuit for said device; means for imparting a step by step rotation to said member comprising a series of elements positioned on said member, a plurality of stepping yokes one for each said element, and electromagnetically actuated means for independently operating each stepping yoke; means for returning the member directly to normal position from the position reached by the 70 step by step rotation, and electrically controlled 75

means for retaining said member in certain predetermined positions.

58. In combination with a plurality of railway traffic governing devices, a control panel comprising a panel board with the track layout indicated on the face thereof, a plurality of manually movable indicating members on the face of the panel one corresponding to each said traffic governing device and each by its position indicating the position to be assumed by the corresponding device, a single rotatable element, electromagnetic means under the control of said members for imparting step by step rotation to said element, and contacts controlled by said element for selectively operating said traffic governing devices into positions of correspondence with the associated indicating members.

59. A centralized traffic control system for railroads comprising an office and a station, a railway switch at the station, signals for governing 20 traffic in opposite directions over said switch, a switch lever and a signal lever at said office each capable of assuming two positions, means at the office for transmitting to the station distinctive codes having characters determined by the positions of both said levers, four relays at the station each selectively responsive to an individual one of said codes and corresponding respectively to four possible combinations of positions of said levers, control means actuated to move said 30 switch to normal and clear a signal for traffic in one direction when one said relay is operated, to move said switch to normal and clear a signal for traffic in the other direction when a second said relay is operated, to move said switch to 35 reverse and clear a signal for traffic in said one direction when a third said relay is operated, and to move the switch to reverse and clear a signal for traffic in said other direction when the fourth said relay is operated, and means for retaining 40 said control means in its actuated condition after the termination of a code.

60. A centralized traffic control system for railroads comprising an office and a station, a railway switch at the station, signals for governing 45 traffic in opposite directions over said switch, a switch lever at the office capable of assuming two positions, a signal lever at the office capable of assuming three positions, means at the office for transmitting to said station one of four distinctive codes each determined by both said levers in their extreme positions and a fifth code when the signal lever occupies its middle position, five relays at the station each selectively 50 responsive to one of said codes, control means actuated to move said switch to normal and clear a signal for traffic in one direction when one said relay is operated, to move said switch to normal and clear a signal for traffic in the other direction when a second said relay is operated, to move said switch to reverse and clear a signal for traffic in said one direction when a third said relay is operated, and to move the switch to reverse and clear a signal for traffic in said other direction when the fourth said 65 relay is operated, and to put all said signals at stop when the fifth said relay is operated, and means for retaining said control means in its actuated condition after the termination of a code.

61. In a dispatching system, a dispatcher's office, a way station, a track switch and signals at said station controllable to set up four possible routes for train movements, four control relays at the station each operable to govern both the 70 75

position of said switch and the indications of said signals to set up one only of said routes, and means for governing said control relays selectively from the dispatcher's office.

5 62. In a dispatching system, a dispatcher's office, a way station, a track switch and signals at said station controllable to set up four possible routes for train movements, four control relays at the station each operable to govern both the 10 position of said switch and the indications of said signals to set up one only of said routes, a fifth relay at said station operable to set all said signals at stop, and means for governing said control relays selectively from said dispatcher's 15 office.

63. In combination with a stretch of railway track including a switch and power mechanism for operating the switch, a control panel comprising a panel board having a miniature representation of the stretch indicated thereon including a miniature switch point manually operable to a normal or to a reverse position to indicate the route to be taken by a train in passing over the switch, and a contact member driven 25 by said miniature switch point for operating the track switch to a position corresponding to the position to which said miniature switch point is operated.

64. In a railway traffic control system, a track layout including a plurality of power operated track switches, a control panel comprising a panel board having a miniature representation of the track layout indicated thereon including a miniature movable switch point for each track 35 switch of the layout, said miniature switch points being manually operable each to a normal or a reverse position to indicate different routes to be established through the track layout, a contact member driven by each said miniature 40 switch point and circuits governed by each contact member for operating the corresponding track switch to a position corresponding to that to which such switch point is moved.

65. In a system for the control of a power-operated railway track switch, a control panel comprising a panel board with a diagram of the track section including the switch indicated on the face thereof, a manually operable control member mounted on said panel board in a location corresponding to the track switch, said control member comprising a movable switch point provided with a handle for moving it to a position corresponding to the position to which the track switch is to be operated, a movable contact attached to said control member, stationary contacts cooperating with said movable contact, and circuits controlled by the stationary and movable contacts for causing the track switch to be operated to its normal position when said 50 switch point is moved to its normal position and for causing the track switch to be operated to its reverse position when said switch point is moved to its reverse position.

66. In a system for the control of a power-operated railway track switch, a control panel comprising a panel board with a diagram of the track section including the switch indicated on the face thereof, a manually operable control member mounted on said panel board in a location corresponding to the track switch, said control member comprising a movable switch point provided with a handle for moving it to a position corresponding to the position to which the track switch is to be operated, said switch point 65 being free to be moved at any time, means asso-

ciated with said control panel for indicating when the track section including the switch becomes unoccupied, a circuit controller mounted on the panel and driven by said control member, and circuits governed by said circuit controller 5 and effective only when said track section is unoccupied for operating the track switch to a position corresponding to that to which said control member is moved.

67. In a system for the control of a power-operated railway track switch, a control panel comprising a panel board with a diagram of the track section including the switch indicated on the face thereof, a manually operable control member mounted on said panel board in a location corresponding to that of the track switch, said control member comprising a movable switch point provided with a handle for moving it to a normal or to a reverse position corresponding to the position to which the track switch is to be 10 operated, a movable contact driven by said control member, a first stationary contact cooperating with the movable contact when said member is in its normal position, a second stationary contact cooperating with the movable 15 contact when said member is in its reverse position, and means rendered effective when said control member is moved from one position to the other for momentarily completing a circuit over the movable contact and the stationary contact 20 then closed, and means responsive to the momentary closing of said circuit for operating the switch to a position corresponding to that occupied by said control member.

68. In a system for the control of a power-operated railway track switch, a control panel comprising a panel board with a diagram of the track section including the switch indicated on the face thereof, a manually operable control member mounted on said panel board in a location corresponding to that of the track switch, said control member comprising a movable switch point provided with a handle for moving it to a normal or to a reverse position corresponding to the position to which the track switch is to be 35 operated, a movable contact driven by said control member, a first stationary contact cooperating with the movable contact when said member is in its normal position, a second stationary contact cooperating with the movable contact when 40 said member is in its reverse position, a third contact closed when said member is moved from either of said positions to the other position, and means responsive to the closing of said third contact for momentarily completing a circuit including said movable contact and one stationary contact or the other depending upon the position to which the member is moved, and means controlled by said circuit for operating the track 45 switch to a position corresponding to that of said member.

69. In a system for the control of a power-operated railway track switch, a control panel comprising a panel board with a diagram of the track section including the switch indicated on the face thereof, a manually operable contact member mounted on said panel board in a location corresponding to that of the track switch, said control member comprising a movable switch point provided with a handle for moving it to 50 a normal or to a reverse position corresponding to the position to which the track switch is to be operated, indication means associated with said panel board for visually indicating the position of said track switch, contact means driven by 55

said control member, means controlled by said contact means for operating the track switch to a position corresponding to that of said control member, and means controlled by said track switch for controlling said indication means.

5 70. In a railway traffic control system, a track layout including a plurality of power operated track switches, a control panel comprising a miniature diagram of the track layout having a manually movable control member for each track switch of the layout, said control members comprising route indicating members movable to cooperate with different parts of the track diagram to indicate different routes through the diagram corresponding to different routes to be established through the track layout, a contact member attached to and controlled by each route indicating member, and circuits controlled by said contact members effective to cause the track switches to be operated when traffic conditions are favorable to establish the route through the layout indicated by the relative positions of said route indicating members with respect to said track diagram.

10 71. In power operated railway switch and signal mechanism, a control panel comprising a miniature diagram of a track layout including a track switch, said panel including a first manually movable control member corresponding to the track switch having a route indicating member movable on the face of the panel to cooperate with the track diagram to indicate different routes through the layout, a contact member driven by said indicating member for controlling the track switch, a second manually movable control member having an indicating member movable on the face of the panel to indicate the direction of train movement to be established over the track switch and a contact member driven by said indicating member for controlling signals governing the movement of traffic over the switch.

15 72. In a railway traffic control system, a stretch of railway track including a power operated railway track switch, a first signal for governing the movement of traffic into said stretch when the switch is normal, a second signal for governing the movement of traffic into said stretch when the switch is reversed, a control panel comprising a miniature diagram of said stretch and including a manually movable switch point located to correspond to the location of the track switch and provided with a handle for moving it to a normal or to a reverse position corresponding to the position to which the track switch is to be operated, a manually movable signal control

member mounted on said control panel, a first movable contact controlled by said movable switch point, a second movable contact controlled by said signal control member, means controlled by said first movable contact for operating the track switch to the position indicated by said switch point, and means controlled jointly by said first and said second movable contacts and by the track switch for clearing one signal or the other depending upon the position of the track switch but only when the track switch and the movable switch point occupy corresponding positions.

10 73. Apparatus for the remote control of three-position movable devices comprising a line circuit, transmitting means arranged to deliver codes to said line circuit comprising different series of code elements each element having a selected one of three possible characters, said elements being arranged in different orders in different codes, receiving means controlled by the code elements delivered to said line circuit comprising selecting means supplied with each element of a code and selectively responsive to the character of such element, stepping means controlled by said selecting means arranged to register the successive elements of a code, means controlled by said stepping means in accordance with the order in which a plurality of the elements are received for selecting a particular device for operation, and means operating the selected device to one of its three positions in accordance with the character of one element of the code.

15 74. Apparatus for the remote control of movable devices comprising a line circuit, transmitting means arranged to deliver codes to said line circuit comprising different series of code elements each element having a selected one of three possible characters, said elements being arranged in different orders in different codes, receiving means controlled by the code elements delivered to said line circuit comprising selecting means supplied with each element of a code and selectively responsive to the character of such element, stepping means controlled by said selecting means arranged to register the successive elements of a code, means controlled by said stepping means in accordance with the order in which a plurality of the elements are received for selecting a particular group of movable devices for operation, and means operating each of such devices, each in accordance with the character of a different one of the remaining elements of the code.
